UNITED STATES PATENT OFFICE.

LEONARD LEWIS, OF NEW YORK, N. Y.

BUILT-IN FIRE-EXTINGUISHER HOLDER.

Application filed November 24, 1926. Serial No. 150,584.

This invention relates to embedded holders for fire extinguishers and particularly to an improved built-in holder merging into the wall in which it is fitted while at the same time permitting easy access to the extinguisher.

Another object of the invention is to provide a built-in holder for fire extinguishers wherein the casing or body of the holder merges into the molding which in turn merges into an expanded metal portion interlocking with the plaster of the wall.

A still further object of the invention is to provide a built-in holder for fire extinguishers, the same being formed of sheet metal or other fire proof metal and so constructed that the same may be formed in one piece or in several pieces and joined together.

20 In the accompanying drawing—

Figure 1 is a horizontal sectional view through part of a wall with a built-in holder shown connected therewith, said holder disclosing an embodiment of the invention.

25 Figure 2 is a sectional view through Figure 1, approximately on line 2—2.

Figure 3 is a reduced front view of the holder shown in Figure 1, the holder being removed from the wall.

30 Referring to the accompanying drawing by numerals, 1 indicates a wall which is provided with plaster surfaces 2 and 3 and any suitable kind of frame 4. Connected with the frame 4 are top and bottom plates 5 and

35 6, which with the side plates 7 and 8 and part of the wall 1, form a chamber 9. It will be noted that the wall 1 is cut away at one point so as to receive what may be termed the container 10. This is shown as a

40 substantially semi-circular piece of sheet metal having ends 11 and 12, said ends and the sides of member 10 merging into a molding 13, which in turn merges into an expanded metal section 14.

45 As shown in the drawing, all of the parts just described are integral and formed of sheet metal but if desired, they could be made in a number of parts and connected together in any desired manner, as for instance, by welding or soldering. Also, the

parts could be made of other material than metal without departing from the spirit of the invention, as for instance, pottery. Also, the shape disclosed is a preferable shape as it permits the hand of a person to be readily inserted for grasping the fire extinguisher 55 but if desired, the shape could be changed without departing from the spirit of the invention, provided of course, a sufficient opening was allowed to permit the extinguisher 60 15 to be removed and applied freely. The extinguisher 15 is held in place by a suitable clip 16, riveted or otherwise secured at 17 to the rear part of the container 10. The device is adapted for use in many places, as 65 for instance, in the kitchen and halls of homes and also in theatres and other public places.

What I claim is:

1. A built-in fire extinguisher holder comprising a sheet metal container open on one side, integral top and bottom members, and a molding encircling the open side of the container and formed integral with the container and said members. 70

2. A built-in container for fire extinguishers comprising a substantially rectangular molding, an expanded metal section extending from one edge of the molding for interlocking with the plaster of the wall when 80 the device is in use, and a container extending from the other edge of the molding, said container, molding and expanded metal being of one piece of sheet metal.

3. A built-in holder for fire extinguishers comprising a fire proof container, and means for connecting the container to a wall, said means including expanded metal extensions from the top and side edges of the container. 85

4. A built-in holder for fire extinguishers comprising a fire proof container of sheet metal adapted to be set into a wall, said container having expanded top, and side edge extensions and a curved bottom extension merging into the wall structure and acting 90 to produce a finished appearance and at the same time anchoring means for holding the container in place. 95

LEONARD LEWIS.
